FRANK E. GARBUZZ AND LEIGH M. GRIFFITH, OF LOS ANGELES, CALIFORNIA, ASSIGNEES TO PARAMOUNT FAMOUS LASKY CORPORATION, OF NEW YORK, N. Y., A CORPORATION OF NEW YORK.

FILM-DEVELOPING MACHINE.

Application filed April 26, 1926. Serial No. 104,609.

Our invention relates to film developing machines in which the film is fed over suitable rollers through various tanks for the purpose of performing the developing, fixing, washing and drying operations thereon. The film during these operations expands and contracts and the invention is so constructed that it automatically compensates for such expansion and contraction and maintains a substantially uniform tension on the film at all times. This is important since the film must be maintained under a minimum tension to prevent the film buckling against the walls of the apparatus or against itself, and to prevent kinking. At the same time the mechanical strength of the film is small and we provide means by which the maximum tension to which the film can be subjected is strictly limited. This prevents the film from being broken or distorted by the application of too much tension thereto.

The problem of maintaining the film under uniform tension in such continuous developing machines has been long recognized and previous inventors have sought to solve this problem by providing means adapted to drive the film at a speed somewhat higher than that desired and then allowing the film to be frictionally driven so that there is a constant slippage whenever the tension on the film exceeds a safe maximum value between the film itself and its driving means or between suitable friction surfaces between the film and the ultimate driving means. All such frictional drives with which we are familiar are unsatisfactory due to variations in friction under the conditions of operation met in practice, so that such machines need constant attention and frequent repairs and are most unsatisfactory from a user's viewpoint.

It is an object of our invention to provide a continuous film developing machine in which the film is positively driven at intervals through the machine by driving means whose driving force is fixed within such limits that a uniform tension is maintained on the film, and which is so constituted that the film is driven faster or slower whenever it is necessary to maintain this tension. This we accomplish without using friction or friction clutches, the driving force being au-

tomatically regulated to maintain a uniform and definite tension on the film, regardless of its speed. In the embodiment of the invention shown herein, we employ a plurality of impulse wheels operated by fluid jets whose force may at all times be accurately regulated to provide uniform tension on the film. Such an arrangement automatically compensates for any shrinkage or expansion of the film.

By employing driving means which pull uniformly on the film regardless of its speed, we are able to regulate the speed of the machine by positively controlling the rate at which the film is fed into the machine at its intake end. If this rate is increased, the impulse wheel automatically speeds up to maintain the tension; and if the rate is greatly reduced, there is no increase in tension on the film. Our invention is broadly new and basic in that it employs means for positively driving the film at uniform tension regardless of speed variations. It is also broadly new and basic in that the rate of feed through the machine is regulated by the rate at which the film is fed into the intake end of the machine, which automatically adjusts itself to this rate.

It is a further object of our invention to provide at the intake end of the machine positive means for accurately regulating the rate of feed into the machine and thus, as explained above, providing means by which the operator may regulate the rate of feed in the machine itself.

In the practical operation of such a developing machine it is highly desirable that the machine be operated continuously over long periods, since successful development requires that the time during which the film remains in the developing solution shall be accurately regulated. Since the film is ordinarily delivered to the developing room in reels containing one thousand feet of film, it is necessary to splice the inner end of the film from the reel being developed to the outer end of a succeeding reel if continuous operation is to be maintained.

It is a further object of the invention to provide means for so splicing without interrupting or varying the rate of travel of the film through the machine, thus insuring continuous and uniform development.

Although it is possible by the use of standardized solutions and films to provide for continuous operation of such a machine, it is desirable that the operator check the 6 operation by visual inspection of the film from time to time during the progress of the development, and it is a further object of the invention to provide means for doing this.

10 The film should be inspected when it leaves the developing solution tank in order to discern whether or not the film has been properly developed. This is commonly done by holding a colored light directly adjacent 15 to the film so that the images will be partially illuminated. The light is generally moved with the film so that a single frame may be observed over a period of a few seconds. This method and means of inspection 20 is not entirely satisfactory and is not as accurate as it might be, since it depends upon manual movement of the light.

It is another object of this invention to provide a film developing apparatus in 25 which the film may be conveniently and accurately inspected.

It is a still further object of our invention to provide a film developing apparatus having a novel design of inspection device. Our 30 conception includes an inspection belt having windows therein, which belt passes over a light box. The film moves in contact with the belt, moving this belt, and said frames of the film are illuminated when the windows pass over the light box.

Other objects and advantages of this invention will be thoroughly explained in the following description taken in connection with the drawings, in which we illustrate 40 our invention.

Referring to these drawings,

Fig. 20 is a partially sectioned view of the 85 inspection device taken as indicated by the arrow 20 of Fig. 19.

Fig. 21 is a section taken on a line 21-21 of Fig. 19.

The form of our invention shown in the 90 drawings consists of a splicer 25, a film feed device 26, a combined branding machine and brake 27, a film take-up 28, a film feed regulator 29, a wet box 30, and an inspection device 31.

In the drawings we illustrate a double machine suited to simultaneously develop two films, all of the apparatus being in pairs; for example, there being a right-hand and a left-hand wet box, etc., In the description, 100 however, we shall describe only the right-hand parts of the apparatus, it being understood that the numerals are applicable to identical parts of the left-hand apparatus, portions of which are shown wherever necessary to a complete understanding of the apparatus.

The film feed device 26 consists of a standard 40 to which reel supporting arms 41 are secured, these reel supporting arms 41 rotatably supporting feed reels 42 and 43. A film 44, which is shown as being carried on the feed reel 42, is extended therefrom to the branding machine and brake 27.

This branding machine and brake is 115 shown and described in detail in our co-pending application entitled Branding machine, filed April 26, 1926, Serial No. 104,610, to which reference may be had if desired. This branding machine and brake 120 consists of a rotor 45 around which the film 44 passes, spools 46 for holding the film 44 in contact with the rotor 45 and a brake mechanism which is operated by a brake lever 48.

It should be noted that the splicer 25, the film feed device 26 and the branding machine and brake 27 are all carried on a table 49.

The film 44 extends from the branding 130

machine and brake 27 to the film take-up 28.

In describing the film take-up, reference is had to Figs. 4 and 5. The film take-up 28 has vertical guides 50, the lower ends of which are attached to a floor 51 and the upper ends of which are attached to a ceiling board 52 which is secured to ceiling beams 53. Directly adjacent to the upper ends of the vertical guides 50 there are secured brackets 55, which support an upper shaft 56 which extends between the vertical guides 50. Pulleys 57 are rotatably carried on the upper shaft 56. Carried between the vertical guides 50 near the lower ends thereof is a carriage 59. This carriage 59 is composed of a frame which has cross bars 60 and vertical end bars 61. At the upper and lower ends of the vertical bars 61 are wheels 63 which are rotatably carried on pins 64 which are secured to the ends of the vertical arms 61. These wheels 63 are adapted to engage the inner faces of the vertical guides 50, and the carriage is thereby rendered movable in a vertical direction. Secured to the vertical bars 61, centrally between the cross bars 60, are brackets 66 which support a lower shaft 67. Rotatably carried on the lower shaft 67 are lower traveling spools 68. As shown clearly in Figs. 4 and 5, the film 44 is wound in loops 69 around pairs of stationary spools 57 and traveling rollers 68.

The purpose of the film take-up is to supply film to the following apparatus of the invention, even though the forward end of the film is constrained from movement. Such a condition as this occurs when the end of the film 44 is reached and another film which may be carried by the reel 43 is spliced thereto. The brake lever 48 is actuated so as to apply the brake of the branding machine and brake 27, which prevents the forward end of the film 44 from moving while a splice is being made. During this time the rest of the apparatus may continue to operate. The carriage 59 will move upwardly on the guides 50 and the loop 69 of the film will shorten and in this manner film will be fed to the following apparatus.

The film extends from the film take-up 28 to the film feed regulator 29 which is illustrated in detail in Figs. 6, 7 and 8.

The film feed regulator has a base 72 which provides a gear chamber 73. The upper part of the gear chamber 73 has an opening and a connector 75 is secured to the base 72 by cap screws 76 in such a manner that the opening through the connector 75 communicates with the gear chamber 73. Secured to the upper end of the connector 75 by means of cap screws 77 is a lower gear housing 78, to the upper end of which a vertical tube 79 is connected. The upper end of the vertical tube 79 is provided with

a flange member 80 and secured to the flange member 80 by cap screws 81 is an upper gear housing 82.

A motor 84 is secured to the base 72 and extending from the motor 84 into the gear chamber 73 is a motor shaft 85. A worm 87 is secured on the shaft 85 in the gear chamber 73. This worm 87 is adapted to drive a worm gear 88 which is keyed on a sleeve 89, which sleeve 89 is secured to the lower end of a vertical shaft 90, this vertical shaft 90 extending upwardly through the connector 75, the lower gear housing 78, the tube 79, and terminating in the upper gear housing 82.

Secured to the lower end of the sleeve 89 by means of a bolt 92 is a ball bearing 93, which ball bearing 93 rests in a cavity 94 of the base formed directly below and in communication with the gear chamber 73. Secured to the vertical shaft 90 inside the lower gear housing 78 is a sleeve 96. This sleeve 96 has a ball bearing 97 secured thereto by means of a nut 98. The ball bearing 97 is retained by a cup 100 which engages the outer race of the bearing and which is secured in place by means of the cap screws 77.

Secured on the sleeve 96 is a gear 101 which engages and drives a gear 102. As shown specifically in Fig. 7, the gear 102 is keyed to a lower spindle 103. This lower spindle 103 extends through the lower gear housing 78 and is journaled in bearings 104 and 105. The bearing 104 is secured against an annular shoulder 107 by means of a nut 108 which is secured to the lower gear housing 78 and through which the lower spindle 103 passes. The bearing 105 is placed in a cylindrical opening 110, the outer end of which opening 110 is closed by a cover 111, through which the small end of the spindle 103 extends. An end 112 of the lower spindle 103 extends horizontally from the lower gear housing 78 and has a lower roller 114 tightly secured thereon by means of a nut 115 which clamps the lower roller 114 against an annular shoulder 116 of the lower spindle 103. The lower roller 114 is formed so as to provide a plurality of spools 118.

The upper end of the vertical shaft 90 has a sleeve 120 secured thereto, on which a ball bearing 121 is secured by a nut 122. The outer ring of the ball bearing 121 rests in a cylindrical opening 124 of the upper gear housing 82. Secured on the sleeve 120 is a gear 125 which engages and drives a gear 126. The gear 126 is secured on an upper spindle 127. The upper spindle 127 is rotatably supported by bearings 128 and 129. The bearing 128 is secured against an annular shoulder 130, by means of a nut 131, which nut 131 has an opening 132 through which the upper spindle 127 extends. The bearing 129 is placed in a cylindrical open-

ing 134, the outer end of which opening 134 is closed by a cap 135. An end 137 of the upper spindle 127 extends horizontally from the upper gear housing 82 and has an upper 5 roller 138 secured thereto. The roller 138 is secured in place by means of a nut 139 which clamps the roller 138 against an annular shoulder 140 of the upper spindle 127. The upper roller 138 is formed so as to provide a 10 plurality of spools 141.

As illustrated in Fig. 1, the film 44 is wrapped around the spools 141 and 118 in loops 142. The motor 84 is a variable speed motor and may be made to operate at the 15 desired R. P. M. by operation of a rheostat or other control device (not shown). When the motor 84 is in operation the worm 87 is driven by means of the shaft 85, and it rotates the vertical shaft 90 through the gear 20 88. The upper and lower spindles 127 and 112 are driven by means of their respective gearing from the vertical shaft 90 and the upper and lower rollers 138 and 114 are rotated at the same R. P. M. The film 44 is 25 looped around the upper and lower rollers a sufficient number of times to procure friction on the film sufficient to drive it and to positively feed it into the wet and dry boxes 30 and 32.

30 The film feed regulator is provided for the purpose of feeding, and functions in a manner to feed, the film 44 at a desired rate of speed to the wet and dry boxes. The rate of feed of the film may be readily changed 35 by merely operating the rheostat or control device of the motor in order to change the R. P. M. thereof accordingly. The rate of feed of the film may be discerned from a speed indicator 144 which is placed on the 40 table 49. This speed indicator 144 is provided with a flexible shaft 145 which extends through a flexible tube 146. One end of the flexible tube and shaft is supported by a bracket 147 which forms a part of the lower 45 gear housing 78. Secured to the end of the shaft 145 is a gear 148 which engages and is driven by a gear 149 which is secured on the extending end of the lower spindle 103, which end is opposite the end 112 of the spindle 50 103. When the film feed regulator is in operation, the flexible shaft 145 is rotated by means of the gears 148 and 149 and the speed indicator 144 is caused to indicate the rate of feed of the film.

55 The film 44 extends from the film feed regulator 29 to the wet box 30. Placed between the wet box 30 and the film feed regulator 29 is a vertical partition board 150 which has an opening 151 through which the 60 film 44 extends.

In describing the details of the wet box, reference will be had to Fig. 1 and 9 to 13 inclusive. The wet box 30 includes tanks 155 which are supported by foundations 156. 65 The tanks may be divided into various com-

partments in which the various solutions for treating the film are retained. In each of the tanks 155 is a film handling unit 157, one of which units is shown clearly in Figs. 9 to 13 inclusive. Each of the film handling 70 units consists of an impulse turbine case 160 which includes a shell 161 and a cover 162. The shell 161 provides an elongated chamber 163 which is open at the top. The cover 162 is secured to the upper part of the 75 shell 161 by cap screws 164 in order to close the upper open end of the chamber 163. Vertical drain tubes 165 extend downwardly from the case 160 and are secured to the shell 161 in communication with openings 80 166 thereof by means of shoes 167, these shoes 167 being secured to the shell 161 by cap screws 168. The vertical tubes of each of the film handling units 157 telescope 85 inside a vertical pipe 170, these vertical pipes 170 being rigidly held at the side of a tank 155 by means of upper and lower brackets 171 and 172. Lower faces 174 of the shoes 167 engage upper faces 175 of the upper 90 brackets 171 and in this manner the film handling units are supported. The lower ends of the vertical pipe 170 connect to a main drain pipe 176, as shown in Fig. 1. This main drain pipe 176 is placed below the floor 95 51. By extending the drain tubes of the film handling units inside the vertical pipe, the units are retained in proper working position.

Referring more particularly to Fig. 11, a front wall 178 of each of the shells 161 is 100 provided with a plurality of front cylindrical openings 179, and a rear wall 180 of each of the shells 161 is provided with a series of cylindrical openings 181 which align with the openings 179. A bearing holder 182 is secured in each of the front openings 179 and a bearing 183 is secured in cavities 184 of each of the bearing holders 182 by means of a retaining cap 186. In each of the back 105 openings 181 there is placed a bearing 187 which is accessible when a cover 188 which closes each of the openings 181 is removed. Each pair of bearings 183 and 187 is adapted to rotatably support an upper drive shaft 190. An inner end 191 of each drive shaft 190 extends into the chamber 163 and has bearings 183 and 187 secured thereto. Each shaft 190 is enlarged at 193 so as to provide a shoulder 194. The bearings 183 and 187 are secured in place by means of a nut 195 which is secured on the inner end of each of the shafts 190, the bearings being clamped between the nut 195 and the shoulder 194. Spacers 197 are placed on each of the shafts 190 between the bearings 183 and 187. Each upper or drive shaft 190 extends 110 horizontally above one of the tanks 155 and has an upper or drive roller 199 attached thereto. Each upper drive roller 199 is rigidly secured to one of the drive shafts 190 115 120 125 130

by means of a nut 200 which is screwed onto the end thereof and which clamps the drive roller 199 against a spacer 201, which in turn engages the enlarged portion 193 of each shaft 190. Each drive roller 199 is divided into a plurality of spools 203.

Secured on each drive shaft 190 inside one of the chambers 163 and between sleeves 197 is a worm gear 204. Each worm gear 204 is engaged by a worm 205 which is rigidly secured on an impulse wheel shaft 206. Each impulse wheel shaft 206 is supported by a bracket 207.

As shown best in Figs. 9, 11 and 12, each bracket 207 is provided with side flanges 209 which rest on inner parts 210 of upper faces of each shell 161. Screws 213 are provided which secure each of the brackets 207 in place. The opposite ends of each bracket 207 have bearings 214 in which each impulse wheel shaft 206 is journaled, each worm 205 being situated between bearings 214. One end of each of the impulse wheel shafts 206 extends outwardly from one side of each bracket 207 and an impulse wheel 217 is secured thereto. Each impulse wheel 217 is of somewhat standard construction and is provided with a multiplicity of buckets 218.

Above each impulse wheel 217 in each of the covers 162 is a cylindrical opening 220. Secured to the covers 162 directly above each opening 220 is a nozzle head 221. Each nozzle head 221 has a cylindrical projection 222 which projects into one of the cylindrical openings 220. Formed in the lower part of each nozzle head 221 and extending through each projection 222 is a passage 224. A nozzle 225 is carried by each of the projections 222 in communication with one of the passages 224. Each nozzle 225 extends partially into one of the chambers 163 and is situated in a position directly above an impulse wheel 217. Each passage 224, as illustrated best in Fig. 12, is connected to a lateral passage 227 formed in one of the covers 162. Each of the lateral passages 227 connects to a manifold passage 228 which is also provided in each of the covers 162.

Referring to Fig. 9, each manifold passage 228 connects to the exterior of each cover 162 near the central part thereof and secured in communication therewith is a return bend 230, each return bend 230 being secured to one of the covers 162 by cap screws 231. The return bends 230 are placed so as to extend to the back of the film handling units 157 and the inner ends thereof are connected to hose 232. Referring to Fig. 1, each hose 232 is connected to a vertical liquid feed pipe 234, each having a valve 235 which controls a flow of liquid through the hose 232. The vertical liquid feed pipes 234 connect to a main liquid feed pipe 236 which extends below the floor 51 and which is provided with a main valve 237. The

hose 232 are provided so as to eliminate any rigid connection of the film handling units and thus permit them to be elevated out of the tanks 155 for the purpose of threading the film through and for inspection or repair of the film handling units. 70

When the main valve 237 and the valve 235 are opened, liquid which is preferably oil under pressure is delivered through the hose 232 to the manifold passage 228 of the film delivering units 157. The liquid passes therefrom through the lateral passages 227 and through the nozzles 225 in the form of jets which impinge against the impulse wheels 217 and cause them to rotate. In 80 this manner the drive rollers of the film handling units are operated through the interconnecting parts. The rate of rotation of the drive rollers depends upon the torque exerted by the impulse turbines which depends upon the character of the jets impinging against the impulse wheels 217. Each of the impulse turbines is therefore provided with a control valve 240 which is carried in one of the nozzle heads 221. Each control valve has a needle 241 which extends downwardly through one of the passages 224 and into one of the nozzles 225. Each control valve 240 also has an upper cylindrical body 243 which rests in a vertical cylindrical opening 244 of each of the nozzle heads 221. 85

As we have heretofore mentioned, it is not necessary to govern each of the impulse turbines by the tension of the film and we therefore show alternate valves which are "fixed" and alternate valves which are "governed". 100

The fixed valves of the invention, as shown best in Fig. 13, each have an enlarged threaded portion 246 formed near the upper end which is screwed in an upper threaded cavity 247 formed at the upper end of each of the nozzle heads 221 and at the upper end of a cylindrical opening 244 thereof. Each of the fixed nozzles is provided with an upper threaded stem 248 above the enlarged threaded portion 246 on which a lock nut 249 is secured. Each lock nut 249 engages an upper end of one of the nozzle heads 221 and thus locks the fixed control valve in place. The upper end of each of the nozzle heads 221 is provided with a cover 257 and each cover 257 conceals the upper end of each control valve and lock nut. The fixed valves are manually adjusted so that a mean rate 115 of speed of the fixed impulse turbines is acquired.

The governed control valves are typically shown best in Figs. 12 and 13. Each control valve 240 which is governed is provided with a horizontal slot 250 in which a cam 251 rests, each cam 251 being forced on the inner end of a horizontal shaft 252. Each shaft 252 extends through a bearing opening 253 of a bearing member 254. 120 125 130

Each bearing member 254 is provided with an inner threaded plug 255 which extends into a threaded socket 256 provided by each nozzle head 221. The nozzle heads 221 of the fixed nozzles have the threaded sockets 256 thereof closed by a plug 258, since the governor mechanisms are eliminated therein.

Secured to the outer end of each shaft 252 is a governor arm 259 from the outer end of which a shaft 260 extends. On each shaft 260 there is a governor spool 262 which is rotatable thereon. A coil spring 264 surrounds a part 265 of each of the bearings 254. The inner end of each of the coil springs 264 engages a pin 267 supported by the bearing 254 and the outer end of each coil spring 264 engages a pin 268 which is supported by a lug 269 of each of the governor arms 259. Each coil spring 264 is for the purpose of resiliently raising the governor arm into its highest position.

When the governor arms 259 are in their highest position the cams 251 are in such a position that the control valves 240 associated therewith are raised and there is therefore a maximum jet of liquid flowing through each of the nozzles 225 and each of the impulse wheels 217 is being driven at their maximum torque. When the governor arms 259 are in their lowest position, the cams 251 are in such positions that the valves 240 are in their lowermost position. At this time there is a minimum size jet flowing through each of the nozzles 225 and therefore each of the impulse wheels 217 is being driven at a minimum torque. The manner of controlling the different positions of the governor arms 259 will be explained hereinafter.

Since it is necessary to quite accurately govern the speed of the governed impulse turbines, it is necessary to preserve the valve seat 266 provided at the lower ends of each of the nozzles 225. It is therefore necessary to prevent the lower ends of the needles 241 from pressurably engaging these seats 266 and this is done by means of the construction which is shown best in Fig. 12. The upper ends of the governed control valves 240 are provided with threaded cavities 247 into which stop pins 270 are screwed. Each stop pin 270 is slotted as indicated at 271 and the lower ends thereof are expanded so that when it is screwed into a cavity 272 there will be a resilient pressure thereof against the walls of this cavity which tend to prevent it from rotating and getting out of adjustment. Screwed into the threaded socket 247 of the nozzle heads 221 in which each of the governed control valves is situated is a stop 273, the upper part of which may be engaged by a head 274 formed at the upper end of each of the stop pins 270. Each pin 270 is adjusted so that the head thereof may engage one of the stops 273 just

before the pin of the associated control valve comes into engagement with one of the valve seats 266.

Each of the film handling units also includes a cradle 275. Each cradle 275 includes a plurality of horizontally extending bars 276 which extend below certain of the drive rollers 199. Each horizontal bar 276 extends into a socket 277 formed on the front wall 178 of each of the cases 160. Placed on each bar 276 at the opposite ends thereof are brackets 279 which are spaced apart by means of a tubular spacer 280 which surrounds one of the horizontal bars 276. Connected to the pairs of brackets 279 are pairs of vertical cradle bars 281, the lower ends of which bars 281 are connected by plates 283 to horizontal side bars 284. The horizontal side bars 284 are retained in proper spaced relationship by the cross bars 285 which have tongues 286 extending through openings provided therein. Extending through the outer ends of the tongues 286 are pins 287 which lock the side bars and cross bars together. Extending between and secured to the side bars 284 of each of the cradles 275 are lower shafts 289, each of which carries a lower or driven roller 290. Each of the driven rollers 290 consists of individual lower or driven spools 291. The cross bars 285 of the cradles 275 carry longitudinal film guides 293 which extend in positions directly adjacent to adjacent parts of the individual spools 291.

The film 44 passes to the wet box 30 through the opening 151 and extends over the first governor spool 262. The film extends from the first governor spool 262 to the first drive roller 199 and then to the first driven roller 290. The film is wrapped around the consecutive spools 203 and 291 of the first series of upper and lower rollers 199 and 290 in the form of loops 300. The film passes from the first series of upper and lower rollers directly to the second series of upper and lower rollers as illustrated best in Fig. 9. The film is wrapped around the second series and then passes over the governor spool 262 of the second governor and then to a third series of upper and lower rollers. It should be noted that there is one governor mechanism for every two series of upper and lower rollers. Therefore, we may consider the upper and lower rollers as being in pairs, each of which is provided with a governor mechanism.

In explaining the operation of the governor mechanism shown in Fig. 9, we will number the first governor mechanism 301, the second governor mechanism 302 and the third governor mechanism 303. The first series of upper and lower rollers will be numbered 305, the second series will be numbered 306, the third series 307, the fourth series 308, and the fifth series 309. As previously mentioned, the governor mechanism

is provided for the purpose of maintaining the film at a normal tension regardless of the speed at which it is fed to the machine and regardless of the stretch and shrink of the film.

The operation is substantially as follows:

If the tension in the first series 305 decreases the governor arm 259 of the first governor mechanism 301 moves upward, and as previously explained this will raise the control valve connected therewith in a manner to increase the torque or driving power of the impulse turbine associated therewith. This tends to drive the upper roller or drive roller of the first series 305 at a higher rate of speed and consequently the film is taken by this series 305 at a speed commensurate with the feed of the film thereto, and the tension at this point will be returned to normal and the first governor mechanism 301 will be returned to normal position.

When the first series of rollers 305 is accelerated in speed, the film is fed at a higher rate of speed to the second series 306 and the tension therein is reduced. The governor arm 259 of the second governor mechanism 302 at this time is permitted to raise and the control valve associated with this governor arm is operated so as to speed up the operation of the third impulse turbine. This causes the drive roller of the third series of rollers 307 to operate at a higher rate of speed, and relieves the second series of rollers 306 of any pull, thereby speeding it up, which allows the tension of the film around the second series of rollers 306 to return to normal. The fourth and fifth series of rollers and the third governor mechanism are affected in the same manner as the second and third series of rollers 306 and 307, and the second governor mechanism 302 is affected when the tension in the first series of rollers is decreased.

When the tension in the first series of rollers 305 increases, the arm of the first governor mechanism is lowered and the control valve associated therewith is moved into position to restrict the flow of fluid and the impulse turbine is run at a slower rate of speed. Therefore, the series of rollers 305 decreases in speed and permits the tension thereof to return to normal. When the speed of the first series of rollers 305 is decreased, the film is fed at a slower rate of speed to the second series of rollers 306 and therefore the tension will increase and the governor arm of the second governor mechanism 302 will be depressed. This will slow the third series of rollers 307 and will affect the second series 306 in such a manner as to slow up the speed and return the film tension to normal. The following series of rollers are affected in the same manner as the second series of rollers 306 is affected when the tension in the first series 305 increases.

As stated heretofore, it is highly desirable to remove all of the free treating solutions from the film as it passes from one tank to the other, and to accomplish this purpose we provide squeegee nozzles. As shown best in Figs. 2, 3 and 14 to 18 inclusive, at a point between adjacent compartments of the solution tanks where there is a partition such as indicated at 315, a series of upper and lower rollers is eliminated. In the opening 178 at this point, in place of the bearing retainer 182 there is secured a special casting 316 which closes this opening 187. The upper part of the special casting 316 is provided with a T formation 317, one horizontal end of which is closed by a plug 318. The vertical port 320 of the T formation 317 has a nipple 321 connected thereto, to which a flexible hose 322 is attached.

Referring to Fig. 1, the hose 322 is connected to a vertical air pipe 323 which connects to a main air supply pipe 324 having a control valve 325. A nipple 327 is connected into one of the horizontal outlets of the T formation 317 to which a nozzle head 328 is secured. The nozzle head 328 is adapted to support a pair of squeegee nozzles 329 which are arranged to direct streams of air on each side of the film 44 as it passes from the solution compartment at the left of the partition 315. The film 44 passes upward from the last drive roller of the compartment over an idler spool 331 which is supported by a bracket 332 which is in turn secured to the nozzle head 328. The film 44 passes from the idler spool 331 to a governor spool, and from thence to the first drive roller in the solution compartment at the right of the partition 315.

The construction of the squeegee nozzles 329 is illustrated best in Figs. 15 to 18 inclusive. Each nozzle consists of a body 335 having a cylindrical projection 336 which is threaded at 337 so that it may be screwed to the nozzle head 328. Formed adjacent to the cylindrical portion 336 is a shell 339 with which there cooperates a separate shell member 340. The shell 339 and the shell member 340 are substantially identical in construction, except that they are right-hand and left-hand parts. The shell 339 is formed to provide an air chamber 342 which connects with an opening through the cylindrical projection 336 by means of a semi-circular passage 343. The chamber 342 is in open communication with a mouth 345 which is formed by a projection 346 of the shell 339. The shell member 340 has a chamber 347 which is in open communication with a mouth 348 provided by a projection 349 of the shell member 340. A semi-cylindrical passage 350 is formed in an end wall of the shell member 340 to cooperate with the semi-cylindrical passage 343. The shell member 340 is placed so that a flat perimetric face 351

351 contacts a flat perimetric face 352 of the shell 339. The shell 339 and the shell member 340 are resiliently clamped together by a semi-cylindrical spring 355 which rests in channels 356 provided in those portions of the parts 339 and 340 which form the chambers 343 and 347. The mouths 345 and 348 cooperate to provide an air outlet by means of which a stream of air of elongated cross section is directed against the face of a film. The size of the opening provided by the mouths 345 and 348 is determined by an adjustment screw 357 which is threadedly held by the shell 339 and which has an end 358 which is adapted to contact a portion 359 of the shell member 340. In this manner the projections may be spread apart to provide a larger air outlet as desired. Extending from the shell 339 and from the shell member 340 are ears 360 which may be pressed together manually in order to spread the projections 346 and 349 apart so that the nozzles may be cleaned without dismantling them.

The special casting 316 provides a socket 362 in which one end of a horizontal tubular support 363 is secured. The outer end of the tubular support 363 has an outboard bracket 364 secured to the outer end thereof. The outboard bracket 364 is provided with a split collar 365, the free ends of which are secured together by a bolt 366 in order to clamp it to the end of the tubular support 363. The outboard bracket 364 has an elbow 367 formed integral therewith which is supported from the split collar 365 by a vertical arm 369. Secured to the vertical opening of the elbow 367 is a short nipple 368, to which a flexible hose 373 is secured. The flexible hose 373 is secured to the vertical air pipe 323 and by means of which air is supplied through the flexible hose to the elbow 367. The horizontal opening of the elbow 367 has a nipple 376 secured thereto, and secured to the nipple 376 is a nozzle head 370. The nozzle head 370 supports a pair of outboard nozzles 371 and 372, which are disposed on each side of the film 44 at a point where it passes from the upper last drive rollers of a solution compartment. These nozzles 371 and 372 are constructed the same as the nozzles 329. The film passes over an idler spool 374 which is supported by a bracket 375 attached to the nozzle head 370. The air is under a pressure of about 5 pounds per square inch and is directed, as explained, against the opposite faces of the film 44 and serves to remove by blowing action any surplus liquid collected on the faces of the film.

The film passes from the film handling unit of the first tank 155 to a film inspection device which is illustrated clearly in Figs. 19 to 21 inclusive.

Secured to the end of the gear case of the first unit is a bracket 377. The bracket 377 has a horizontal bar 378 secured thereto,

which extends horizontally from this bracket to the side at which the solution tank 155 is situated. Secured near the end of the bar 378 is a vertical post 379. This vertical post is provided with a split collar 380 which may be clamped by a bolt 381 securely around the bar 378. The post 379 is also braced by a pipe 383 which extends through a cylindrical opening 384 thereof formed directly above the split collar 380. This pipe 383 extends from the outboard nozzle 370. The upper end of the post 379 is provided with a clamp structure 386 in which a shaft portion 387 of a fixture 388 is secured. This fixture 388 forms a central part of a supporting structure and arms 389 extend therefrom in opposite directions. The shaft portion 387 is provided with a head 391 to prevent the shaft from being moved axially from place. The manner of supporting the shaft 387 permits the supporting structure, which includes the fixture 388 and the arms 389, to be secured in a desired position.

At the extending ends of the arms 389 there is secured a bearing housing 395. Each bearing housing 395 provides a bearing chamber 397 in which ball bearings 397 and 398 are placed, the bearing chambers 396 being closed by a cover 399. The bearings 397 and 398 of each of the bearing housings 395 rotatably support a shaft 401 which extends from the bearing chamber 396 through an opening provided in each cover 399. Rigidly secured on the extending end of each shaft 401 is a wheel or pulley 402. A channel 403 is provided in the rim 404 of each of the wheels 402. The wheels 402 are in alignment as illustrated in the drawings, and extended around them and resting in the channels 403 thereof is an opaque endless belt or endless web 406. As illustrated best in Figs. 19 to 21 inclusive, the endless belt 406 is provided with windows 407 which are elongated as shown and which are of about the size of two frames of the film 44.

The fixture 388 is provided with a flange 409 to which flange there is secured a lamp housing 410, being secured thereto by screws 411. Carried inside the housing 410 is a light reflector 412 which is in the form of a section of a parabola. The back of the housing 410 has a fixture 414 secured thereto, which carries a lamp socket 415. The lamp socket 415 projects through an opening in the reflector 412 and carries a lamp 417 inside the reflector 412. The front part of the housing 410 is flat and is closed by a plate of glass 419. The plate of glass 419 extends partially over opposite flanges 420 of the housing 410 and is clamped in place by guide bars 421, the guide bars 421 being secured in place by screws 422. Gasket members 423 are provided around the edges of the glass 419 which are engaged by the guide bars 421 and the flange 420 for the

purpose of preventing any escape of light at these points. The lamp housing 410 is placed in such a position that the endless belt 406 extends across the glass 419 in contact therewith and is guided by guide faces 425 of the guide bars 423.

The film 44 passes from the first film handling unit and engages the endless belt 406 as illustrated best in Fig. 19. The film 44 extends along the endless belt 406 in frictional contact therewith and around the upper wheel or pulley 402. The endless belt and the wheels 402 are moved with the film by reason of the frictional contact between the film and the endless belt. When one of the windows 407 is passing across the glass 419 of the light housing 410, light rays pass therethrough and illuminate a pair of frames of the film so that they may be inspected as to density and so that it may be determined whether or not the film is being developed to a proper extent. It is preferable to employ a colored glass 419 so that the light rays will not be strong enough to have a detrimental effect on the film. The windows 407 are spaced so that as one window moves from the glass 419 another window may move thereon. The intensity of the light being cast on the frames of the film is the same at all times and the film may be conveniently inspected by the inspection device of our invention; therefore, the condition of the film may be very accurately determined.

The film 44 passes from the inspection device 31 to the film handling unit 157 of the next tank 155 of the wet box 30. The construction of the second wet box and film handling unit is substantially the same as the first one just described, and therefore a detailed description thereof is unnecessary. The film passes from the second film handling unit of the wet box and from the wet box to a suitable drying means.

In putting the machine into operation the first time it is necessary to thread a leader film through the entire apparatus. This leader film consists of a piece of film which is used solely for the purpose of guiding the other film through the apparatus when the machine is first started up. The leader film may be readily threaded around the branding machine and brake 27, the film take-up 28 and the film speed regulator 29. In order to thread the leader film on the film carrying units 157, it is necessary to elevate them so that access may be had to both the upper and lower rollers. The film handling units 157 are elevated by means typically illustrated by hydraulic jacks 505 having rods 506 which are provided with hooks 507 at the lower ends thereof. These hooks 507 engage eyes 508 provided on each of the cases 160. The hydraulic jacks 505 are capable of operation in a manner to lift the

film handling units 157 so that the lower rollers thereof are placed above the tank 155 and so that the leader film may be easily threaded therearound. The purpose of tele-scoping the drain tubes inside the drain pipes and the purpose of providing the flexible hose 232 and the hose 322 and 373 is for permitting the film handling units to be elevated as just described. The film is then threaded around the consecutive spools of the upper and lower rollers and around the governor spools of the first film handling unit 157. It is then passed around the inspection device 31 and around the various spools of the next film handling unit 157. The film handling units 157 are then lowered into proper position inside the tanks 155.

The film to be developed is then connected to the rear end of the leader film and the apparatus is then set into operation. The valves 235 and 237 are opened to supply liquid under pressure to the impulse turbines. This liquid, as previously explained, is preferably in the form of an oil and at a pressure of about 25 pounds per square inch. The motor 84 of the film feed regulator is energized at this time and the whole apparatus begins to operate. When the first part of the film 44 passes from the first tank 155 of the wet box 30, the frames thereof may be inspected at the inspection device 31 so as to determine whether or not the film is being properly developed. If the film is being slightly over-developed or under-developed, the speed of the motor 84 may be varied as previously explained so as to operate the film feed regulator at an appropriate rate of speed. If the film is to be fed faster the film feed regulator is speeded up. This will speed the film handling units 157 and the film handling units 480 in the wet and dry boxes 30 and 32. When the film is being fed faster than what may be termed a normal speed, the governor spools position themselves higher than normal so that the control valves associated therewith will open more and allow a larger jet of liquid so that the turbine motors operate at a higher rate of speed. When the film is traveling slower than normal, the governor spools are in a lower position and the valves are closed more than normal so that the impulse turbines operate at a lower rate of speed. The condition of the film may be inspected from time to time at the inspection device 31 and the development thereof may be kept under accurate control at all times.

When the film 44 carried on the feed reel 42 is nearly all unwound, it is necessary to splice the end of this film with the film which may be carried on the reel 43. When this is to be done, the brake of the machine 27 is applied by actuating the lever 48 and the rear end of the film is locked against move-

ment. The end thereof is then spliced to an end of a film carried on the feed reel 43 by use of the splicer 25. During the time that the rear end of the film 44 is locked from movement the rest of the apparatus still operates. The film is fed to the film feed regulator and the wet and dry boxes 30 and 32 from the film take-up 28 as previously explained.

10 As the apparatus operates while the rear end of the film 44 is held stationary, the loops 69 of the film on the film take-up 28 gradually shorten and the carriage 59 travels upward on the vertical guides 50. The film 15 take-up may carry 250 to 300 feet of film which may be fed to the following apparatus of the machine while the splicing is being made and this gives ample time to make the splice.

20 When the machine is to be shut down the rear end of the film 44 is connected to a leader film which may remain in the machine during the shut-down period, so that when it is again started up the machine will 25 be threaded ready for use, it being only necessary to attach the film to the rear end of the leader.

The foregoing description thoroughly explains the important features, construction 30 and operation of this invention. The important parts of our invention are clearly emphasized in the first part of the description.

It should be clearly understood that the 35 feature of positively driving the drive rollers by individual means is very important. It has been pointed out that where the drive rollers were driven by friction means, the tension of the film was not accurately maintained at a normal tension. It should be quite clear from the foregoing description 40 that a positive and separate drive means for each drive roller will permit an absolute and accurate control of the film and it will be possible to positively keep the film at the desired 45 tension.

The use of an impulse turbine for operating the drive rollers is also very important to the invention. An impulse turbine is susceptible of being very accurately controlled 50 and is therefore sensitive and quick to respond to any variation in the tension of the film. The governor means applied to certain of the impulse turbines is very important 55 as a medium whereby the governed impulse turbines are operated in accordance with the tension of the film.

The inspection device 31 is of a simple design and is carried by one of the film handling units 157 so that it is a part thereof and is always in position for use. The inspection device permits an accurate check of the developing of the film, since the frames of the film may be conveniently observed 65 and emphatically because the light illuminat-

ing the frames is always of the same intensity.

It is believed that the conception of the film feed regulator or any means for feeding the film into the wet and dry boxes is 70 a completely new idea when embodied in the combination shown. The very advantageous part of the combination of the film feed regulator 29 and the film handling units is that the film feed regulator 75 controls the rate of feed of film through the film handling units, which film handling units respond to the feed of the film and operate to maintain the film at proper tension regardless of the rate of speed at which it 80 is fed thereto by means of the film feed regulator 29 and of any stretch or shrink of the film.

The feature of the film take-up 28 is 85 highly desirable since it permits the film developing apparatus to be run continuously even while a splice is being made. As previously pointed out, it may be disastrous to the film to shut down the apparatus at any 90 time while there is a portion of film in the wet box. The film take-up provides a reserve supply of film which may be fed to the following apparatus of the invention, while the rear end thereof is held stationary, such as for the purpose of splicing. 95

We claim as our invention:

1. An apparatus for developing motion picture film comprising: means suited to contain liquids; a plurality of roller means 100 so placed that a single strip of motion picture film may be looped about each of said roller means in a single series passing through said liquid; and a series of prime movers, each independent of the other, and each adapted to drive one of said roller means. 105

2. An apparatus for developing motion picture film comprising: means suited to contain liquids; a plurality of roller means 110 so placed that a single strip of motion picture film may be looped about each of said roller means in a single series passing through said liquid; a series of prime movers, each independent of the other, and each adapted to drive one of said roller means; and means controlled by the tension on said film for regulating the torque of some of 115 said prime movers.

3. An apparatus for developing motion picture film comprising: means suited to contain liquids; a plurality of roller means 120 so placed that a single strip of motion picture film may be looped about each of said roller means in a single series passing through said liquid; a regulating means 125 through which said film is passed before it passes to said roller means; means for regulating the speed of said regulating means and thus controlling the speed at which said film is fed to said roller means; and a series 130

of prime movers, each independent of the other, and each adapted to drive one of said roller means.

4. An apparatus for developing motion picture film comprising: means suited to contain liquids; a plurality of roller means so placed that a single strip of motion picture film may be looped about each of said roller means in a single series passing through said liquid; a regulating means through which said film is passed before it passes to said roller means; means for regulating the speed of said regulating means and thus controlling the speed at which said film is fed to said roller means; a series of prime movers, each independent of the other, and each adapted to drive one of said roller means; and means controlled by the tension on said film for regulating the torque of some of said prime movers.

5. An apparatus for developing motion picture film comprising: means suited to contain liquids; a plurality of roller means so placed that a single strip of motion picture film may be looped about each of said roller means in a single series passing through said liquid; and a series of fluid actuated prime movers, each independent of the other, and each adapted to drive one of said roller means.

6. An apparatus for developing motion picture film comprising: means suited to contain liquids; a plurality of roller means so placed that a single strip of motion picture film may be looped about each of said roller means in a single series passing through said liquid; a series of fluid actuated prime movers, each independent of the other, and each adapted to drive one of said roller means; and means controlled by the tension on said film for regulating the torque of some of said prime movers.

7. An apparatus for developing motion picture film comprising: means suited to contain liquids; a plurality of roller means so placed that a single strip of motion picture film may be looped about each of said roller means in a single series passing through said liquid; a regulating means through which said film is passed before it passes to said roller means; means for regulating the speed of said regulating means and thus controlling the speed at which said film is fed to said roller means; and a series of fluid actuated prime movers, each independent of the other, and each adapted to drive one of said roller means.

8. An apparatus for developing motion picture film comprising: means suited to contain liquids; a plurality of roller means so placed that a single strip of motion picture film may be looped about each of said roller means in a single series passing through said liquid; a regulating means

through which said film is passed before it passes to said roller means; means for regulating the speed of said regulating means and thus controlling the speed at which said film is fed to said roller means; a series of fluid actuated prime movers, each independent of the other, and each adapted to drive one of said roller means; and means controlled by the tension on said film for regulating the torque of some of said prime movers.

9. A film developing apparatus consisting of: film treating means through which a film is passed for developing; a feed reel on which the film is carried; and a film feed regulator through which said film is passed from said feed reel for regulating the rate of feed of the film to said film treating means.

10. A film developing apparatus consisting of: means for developing a film; an opaque endless belt having a window therein; an arrangement for movably supporting said belt, said endless belt adapted to be engaged and moved by said film; a lamp housing over which said endless belt passes; and a lamp in said lamp housing, said lamp illuminating part of said film through said window when it passes in front of said lamp housing.

11. A film developing apparatus consisting of: film treating means through which a film is passed for developing; a feed reel on which the film is carried; and a film take-up through which said film passes before it reaches said film treating means, said film take-up having a stationary roller and a travelling roller around which said film is wound, said travelling roller being movable in a manner to feed film to said treating means even though said film is prevented from being fed to said film takeup.

12. In a film developing machine, the combination of: a series of compartments in which the film is treated; means for guiding the film through said compartments; driving means for pulling the film through said compartments at a uniform tension independent of the speed of travel; and means for positively regulating the rate at which the film is fed into said machine.

13. In a film developing machine, the combination of: a series of compartments in which the film is treated; means for guiding the film through said compartments; driving means for pulling the film through said compartments; means for so regulating said driving means that a uniform tension is maintained on the film regardless of its speed; and means for positively regulating the rate at which the film is fed into said machine.

14. In a film developing machine, the combination of: a series of compartments in

which the film is treated; means for guiding the film through said compartments; a series of driving motors; means by which each motor positively drives the film through said compartments; means for regulating the force exerted by said motors in such a manner as to maintain a uniform tension on the film; and means for positively regulating

the rate at which the film is fed into said machine.

In testimony whereof, we have hereunto set our hands at Los Angeles, California, this 19th day of April, 1926.

FRANK E. GARBUTT.
